[57] **CLAIM**

The ornamental design for a combined industrial diver's underwater light and ultraviolet inspection light, substantially as shown and described.

DESCRIPTION

FIG. 1 is a perspective view of a combined industrial diver's underwater light and ultraviolet inspection light, showing my new design;

FIG. 2 is a rear elevational view thereof on an enlarged scale;

FIG. 3 is a front elevational view thereof on an enlarged scale;

FIG. 4 is a side elevational view thereof on an enlarged scale; and

FIG. 5 is a bottom plan view thereof on an enlarged scale.

FIG. 1

FIG. 2

FIG. 3

FIG. 2

FIG. 5
